(57) **CLAIM**

The ornamental design for a chandelier as shown and described.

DESCRIPTION

The file of this patent contains at least one drawing/photograph executed in color. Copies of this patent with color drawing(s)/photographs(s) will be provided by the Office upon request and payment of the necessary fee.

FIG. 1 is a front elevation view of a first embodiment of a chandelier showing my new design;

FIG. 2 is a rear elevation view thereof;

FIG. 3 is a right side elevation view thereof;

FIG. 4 is a left side elevation thereof;

FIG. 5 is a top plan view thereof;

FIG. 6 is a bottom plan view thereof;

FIG. 7 is a right-top perspective view thereof;

FIG. 8 is a left-bottom perspective view thereof;

FIG. 9 is a front elevation view of a second embodiment of a chandelier showing my new design;

FIG. 10 is a rear elevation view thereof;

FIG. 11 is a right side elevation view thereof;

FIG. 12 is a left side elevation thereof;

FIG. 13 is a top plan view thereof;

FIG. 14 is a bottom plan view thereof;

FIG. 15 is a right-top perspective view thereof;

FIG. 16 is a left-bottom perspective view thereof;

FIG. 17 is a front elevation view of a third embodiment of a chandelier showing my new design;

FIG. 18 is a rear elevation view thereof;

FIG. 19 is a right side elevation view thereof;

FIG. 20 is a left side elevation thereof;

FIG. 21 is a top plan view thereof;

FIG. 22 is a bottom plan view thereof;

FIG. 23 is a right-top perspective view thereof;

FIG. 24 is a left-bottom perspective view thereof;

FIG. 25 is a front elevation view of a fourth embodiment of a chandelier showing my new design;

FIG. 26 is a rear elevation view thereof;

FIG. 27 is a right side elevation view thereof;

FIG. 28 is a left side elevation thereof;

FIG. 29 is a top plan view thereof;

FIG. 30 is a bottom plan view thereof;

(Continued)

FIG. 31 is a right-top perspective view thereof; and, FIG. 32 is a left-bottom perspective view thereof.

1 Claim, 32 Drawing Sheets
